UNITED STATES PATENT OFFICE.

JOHN T. WHITEHOUSE, OF CLEVELAND, OHIO, ASSIGNOR TO THE VAN DORN IRON WORKS COMPANY, OF CLEVELAND, OHIO, A CORPORATION OF OHIO.

JAIL-DOOR-LOCKING MECHANISM.

Application filed April 23, 1923. Serial No. 633,963.

To all whom it may concern:

Be it known that I, JOHN T. WHITEHOUSE, a citizen of the United States, residing at Cleveland, in the county of Cuyahoga and State of Ohio, have invented certain new and useful Improvements in Jail-Door-Locking Mechanism, of which the following is a specification.

This invention relates to improvements in locking mechanism for jail doors and the like.

The objects of this invention are to provide an improved means for indicating open or closed condition of a given door whereby it is impossible for a prisoner to block the door against being closed, without indicating the continued open condition of the door; in other words, to provide an indicating means which will continue to indicate the door as being open until the door is actually and effectively closed and locked.

Another object of this invention is to provide an improved means for moving a single door or any number of doors to open or closed position.

Another object consists in providing an improved means for supporting the door so as to permit adjustment of the same with respect to the doorway and to provide also means for preventing unauthorized tampering with the track and roller by which the door is slidably mounted.

A still further object of this invention is to provide means for locking and removing the covers of the casing which encloses the locking and controlling mechanism for the doors, whereby the mechanism relating to one door may be exposed and the other door mechanisms protected against unauthorized access; furthermore to provide an interlocking connection between the covers for the track box and the pilaster in each case, so that the locking of one of the track box covers will prevent removal of the pilaster cover.

Another object of this invention is to provide a convenient and compact arrangement for the chain connections between the levers and the lock mechanism for an increased number of doors, as for instance when twelve or thirty-four doors are used as illustrated in this case, this compact arrangement for the chains being located in the overhead at the top of the lock box.

Still another object of this invention is to provide a convenient and efficient means of operating the gap nuts for an increased number of doors so as to facilitate the closing and opening operations of such a large number of doors.

In general, the object of this invention is to improve the entire door operating mechanism and locking means therefor so as to render the same secure against unofficial tampering.

In the drawings, Fig. 1 shows in elevation the locking and controlling mechanism of my present invention with the doors in locked position; Fig. 2 is a similar view of one door showing the same in unlocked position with the control lever in fully lowered position; Fig. 3 shows the same as Fig. 2 except that the control lever is returned to horizontal position; Fig. 4 is a detail view of the adjustable gap nut on the pull bar; Fig. 5 shows in elevation the means for locking the covers of the track box above the doors; Fig. 6 is a sectional view taken on line 6—6 of Fig. 5; Fig. 7 is a detail end elevation of one of the covers of the track box; Fig. 8 is a sectional detail view taken on line 8—8 of Fig. 5; Fig. 9 is a detail view in elevation of the locking member for engaging the cover of the track box; Fig. 10 shows in detail plan view the mechanism enclosed within the tripper case; Fig. 11 shows in rear elevation the same mechanism; Fig. 12 is a view like Fig. 10 but with the parts in position corresponding to open position of the door; Fig. 13 is a vertical detail sectional view of a part of the tripper case; Fig. 14 is a detail view in elevation of the hanger member which supports the door in the track box; Figs. 15 to 19 are detail views of the adjustable connection between the top of the door and the hanger member therefor, permitting adjustment of the door with respect to the doorway; Fig. 20 is a front elevation of the lock in unlocked condition, the cover of the lock casing being removed; Figs. 21 and 22 are detail inverted plan views of the lower ends of the operating rods or shafts which connect with the shafts of the lock bolt and shield in the lock case; Fig. 23 is a top plan view of the lock case; Fig. 24 is a sectional view taken on line 24—24 of Fig. 20; Figs. 25, 26 and 27 are detail views show-

ing the several positions of the lost motion connection in the shaft for operation of the locking bolt; the position indicated in Fig. 25 corresponding to closed and locked position of the door with the operating lever in raised position; Fig. 26 corresponding to the position of the door after being unlocked and while opening, with the lever in extreme lowered position, while Fig. 27 corresponds to the position of the door unlocked and open, with the control lever returned to horizontal position; Fig. 28 is a sectional detail view on the line 28-28 of Fig. 20 and corresponds to the unlocked position; Fig. 29 is a similar view of the same in locked position; Fig. 30 is a detail plan view of the door staple; Fig. 31 is a view of the same in elevation; Fig. 32 is a sectional view of the lock bolt; Fig. 33 is an elevation of the same; Fig. 34 is an end view of the same; Fig. 35 is an elevation of the actuating pawl for the lock bolt; Fig. 36 is an elevation of the shield; Fig. 37 shows in front elevation the arrangement of the operating levers, etc., inside of the lock box; Fig. 38 shows in elevation the arrangement of the brackets, rollers and chains for a series of twelve doors, this mechanism being located in the overhead space at the top of the lock box; Fig. 39 shows in plan view the same mechanism as shown in Fig. 38; Fig. 40 is a detail view taken on line 40-40, Fig. 39; Figs. 41, 42 and 43 are detail views taken on lines 41-41, 42-42, and 43-43 of Fig. 38; Fig. 44 is an inverted plan view of the chain guide box upon which the roller brackets are mounted; Fig. 45 is taken on line 45-45 of Fig. 39; Fig. 46 shows in elevation the arrangement of the chains, rollers etc., for operation of a series of thirty-four doors, this mechanism being located in the overhead space at the top of the lock box; Fig. 47 is an inverted plan view of the chain guide box of Fig. 46 and shows the manner of mounting the roller brackets on the bottom thereof; Fig. 48 shows in plan view the same mechanism as shown in Fig. 46; Fig. 49 is a detail view of the improved means for operating the gap nuts when a large number of doors are used; Fig. 50 is a detail view of the stop means provided for the rack bar which forms part of the mechanism shown in Fig. 49; Figs. 51, 52, 53 and 54 are detail views taken on lines 51-51, 52-52, 53-53 and 54-54 of Fig. 46; and Fig. 55 is a view taken on line 55-55, of Fig. 48.

The present improved mechanism may be employed in connection with any number of doors which open into a corridor in front of the cells and which corridor is partitioned off by means of a grating from the warden's room at the end of the row of cells. The door or gate, which leads from the warden's room to the prisoners' corridor is locked by means of the bolt indicated by reference numeral 1 and controlled by means of the lever 2, the warden's room being indicated at the left end of Fig. 1. From this point access may be had to the lock box 3 which is provided with a suitable door and within which are provided the levers for controlling the locking mechanism. The partition 3^a separates the upper part of the lock box from the lower part and there is provided an inner compartment 3^b through which the ends of the levers extend. A door 3^c is also provided for the lock box. In the present case, only two doors are shown and are indicated by reference numeral 4. Extending from the top of the lock box 3 and along the top of the row of cell doors, there is provided the track box 6 within which is enclosed part of the control mechanism and within which the doors are suspended for rolling movement. Upon the back wall of the track box 6 there is provided the angle iron providing a track 7 with a groove for the correspondingly formed rollers 8 which are carried by the doors. These rollers are mounted upon the plates 9 which are secured to the cast hanger members 10. The hanger members have portions 11 extending through the slot 12 in the bottom of the track box and are provided with adjustable supporting connections for the doors, as will be later described. As a means of preventing unauthorized tampering with the door-suspending means just referred to, that is, to prevent insertion of tools and the like up through the slot 12, I have provided an angular strip 13 which is suitably secured within the track box and extends sufficiently rearwardly so as to prevent upward insertion of any such tools or the like. Likewise, the depending portions 11 of the hangers 10 are given the substantially S shape as indicated in Fig. 6 so as to extend around and below the angle members 13 for connection with the doors.

The particular manner of connecting the top of each door to its hanger member is fully illustrated in Figs. 15 to 19 and comprises the screw bolts 14 which extend through the top of the door as well as through the clamping members 15 and have screw-threaded engagement with the lower portions 11 of the hanger members. The clamping members 15, two of which are provided for each door, are provided with suitable ears 16 to which are secured by means of countersunk headed pins 17 the cover members 18 which are of channel shape, these clamping members lying between the depending flanges at the top of each door. As will be seen from the drawings, each of the two depending portions 11 is provided with such suspending connection so that they may be properly adjusted to correct

116
120
125
130

the hanging of the door within the doorway as may be necessary, without disturbing the position of the hanger member, which, of course, must maintain constant 5 rolling position within the track box.

The locking mechanism for the edge of the door is enclosed within the casing 19, which has its own removable cover and which in turn is enclosed within the pilaster 10 20 provided at the side of each doorway. This locking mechanism comprises a lock bolt 21, of the form herein shown, loose upon the vertically extending rock shaft 22, a spring 23 normally tending to force the bolt 21 into locking position. The bifurcated pawl 24, which is fixed upon the vertically extending rock shaft 25 and at a point midway across the casing 19, is adapted to engage the lock bolt 21 at points 15 20 on opposite sides of the bracket 33, to move the bolt into unlocked position, that is, when the shaft 25 is rotated in a counter-clockwise direction as viewed in Fig. 24 of the drawings. The locking pawl 26, which is pivoted at 27 on a bracket ear within the lock casing, is normally forced toward the right, as viewed in Fig. 24, by the spring 28 which engages in a suitable recess in the face of the pawl. These parts are so arranged that the pawl 26 will ride against the face portion 29 of the cam member 24 until the shoulder 30 has passed the end of the pawl 26, whereupon the pawl will be snapped by its spring 28 into engagement 35 with the shoulder 30 so as to maintain the lock bolt in withdrawn or unlocked position as indicated in Fig. 24. The pin 31, which has a flat head 32, extends through and has longitudinal movement in a suitable fixed bracket 33 provided upon the wall of the lock casing. The head 32, by striking the shaft 39 prevents accidental removal of the pin 31, as will be seen from Fig. 24. The plain end of the pin 31 is adapted 40 45 to engage the pawl 26 so as to release the same from engagement with the shoulder 30, whereupon the spring 23 will force the lock bolt 21 into locking position. The bracket 33 serves as a stop to limit the movement of the lock bolt which is cut out at 33^a so as to accommodate the bracket 33. The pin 31 is adapted to be engaged by means of the staple 34 which is carried by the door and which is adapted to project 50 55 through the opening 35 of the lock casing, upon the door being brought to closed position. While the door is in open position, the shield 36 will cover the opening 35 so as to prevent unauthorized tampering with 60 65 the lock mechanism. This shield is fixed for rocking movement upon the same axis 22 as is the lock bolt 21 and is normally forced by means of a spring 37 into position to cover the opening 35 as indicated in Fig. 24; that is to say, upon the staple

being withdrawn from the lock casing, the shield 36 will automatically return to its normal position so as to cover the opening 35. The shield 36 is controlled by means of the pawl 38 which is fixed upon the upwardly extending rock shaft 39 and in the bottom part of the lock case. In the top of the lock case there is fixedly mounted on shaft 39 a member 36^a having a curved finger portion for engagement in a corresponding recess 36^b in the shield when the shield is closed.

The rock shaft 25 is controlled in its operation by means of the lever arm 40 which is enclosed in the lock box 3, it being understood that such a lever is provided for each door. The lever 40 is connected by means of the rod 41 and sprocket chain 42 with the crank member 43 which is fixedly mounted upon the upright shaft 44, chain 42 extending about one of the suitably mounted rollers 42^a and thence through an opening in the back wall of the lock box, as also in the case of chain 42^a. In the case of door No. 2, there is provided a rod 42^b between 90 sprocket chains 42^a and 42^c, thereby effecting like operative connections between the hand lever for door No. 2 and its rock shaft 44. Like operative connections are provided also for the other doors of the row 95 of cells, and suitable supporting brackets are provided for the rod 42^b and other like rods.

The lower end of the shaft 44 has a lost motion connection with the shaft 25 while 100 the upper end of the same terminates in the tripper case 45. Each tripper case has a removable cover. Fixedly mounted upon the upper end of the shaft 44 and at a point within the tripper case 45 is the bell crank lever 46 which has its other end pivotally connected at 47 to the horizontally extending rod 48, while at the middle point 49 of the lever 46 there is anchored one end of a spring 50, the greater portion of which is 105 in the form of a coil 51 with its other end anchored at 52 to a bracket fixed within the tripper case. Fixed upon the shaft 44 just below the bell crank lever 46 there is provided the cam locking member 53 which is 110 provided with a shoulder 54 adapted to be engaged by the pawl 55, which is pivoted at 56 within the tripper case and is normally forced by means of a spring 57 into such locking engagement as to maintain the shaft 44 in position corresponding to unlocked condition of the locking mechanism enclosed in the casing 19. The shaft 58, which has fixed connection as indicated at 59 with the shaft 39 for controlling the position of the shield 36, likewise terminates at its upper end in the tripper case and has fixed thereon at a point within the tripper case, the crank member 60. The coil spring 61, one end of 115 which is anchored at 62 to the wall of the 120 125 130

tripper case, is attached at its other end at 63 to the crank 60 and tends to normally move the same in a clockwise direction as viewed in Fig. 10. At the point 64, the link 65 is pivotally connected to the crank 60 while its other end is pivotally connected at 66 to the finger member 67, which, in turn, is pivotally mounted at 68. The finger member 67 is of sufficient length and is provided furthermore with the flat face portion 69 for engagement by the rollers 70 which are mounted in the block member 71 which in turn is slidably mounted within a rectangular housing 72 formed within the tripper case. The housing 72 joins a housing portion 73 of cylindrical form within which is provided a spiral spring 74 which normally forces the block 71 with the rollers 70 to the right, as viewed in Fig. 12. The shaft 68 of the rollers 70 extends up through the slot 75 in the housing 72 and the rollers engage the wall 76 which is provided with an opening or slot 77 through which extends the finger member 67 when the parts occupy the position indicated in Fig. 12. The finger 67 is of sufficient length as to prevent disengagement of the rollers 70 when moved to the position indicated in Fig. 10. The rollers 70, as will be seen from Fig. 10 of the drawings, when moved toward the left, will engage the finger member 67 and turn the same upon its axis so as to actuate the crank member 60 and hence the shaft 58 against the tension of spring 61. This operation is effected by means of an adjustable plunger 78 which is carried by the bracket portion 79 of the door hanger member. Thus, as the door is moved to closed position, the parts will be operated in the manner just now described so as to rotate the shaft 58 and likewise shaft 39 in a counter-clockwise direction. The shield 36 is thereby withdrawn from the opening 35 and permits entrance of the staple through the said opening so as to engage the headed pin and in turn effect the release of the lock bolt 21 for engagement with the door staple, thereby securely locking the door in closed position.

50 The lost motion connection above referred to between the shaft 44 and the shaft 25 comprises a depending tooth 80 carried by a collar portion 81 adjustably secured to the lower end portion of the shaft 44 by a set screw 81. This connection comprises also a collar portion 82 which is fixed upon the shaft 25 by means of the set screw 83 so as to permit rotatable adjustment of the same. The collar member 82 is provided with upstanding lugs 84 and 85 arranged on opposite sides of the collar and bearing substantially the same angle as here shown. Extending through the studs 84 and 85 are the adjustable screws 86 and 87 which in turn have lock nuts 88 and 89 for securing the same in set position.

The tooth portion 80 extends between the adjacent inner ends of the stop screws 86 and 87 so as to co-operate therewith.

From Figs. 25, 26 and 27 when considered in connection with the mechanism already described, it will be seen that when the lever 40 is first lowered for the purpose of releasing and opening one of the doors, the tooth 80 will move from the position shown in Fig. 25 in a counter-clockwise direction 75 so as to raise the wedge bolt to the position shown in Fig. 2, and will come to occupy the position indicated in Fig. 26 when the lever has been fully depressed to the position indicated in Fig. 2 of the drawings; 80 such extreme movement of the shaft 44 moving the shaft 25 to its extreme position for effecting unlocking of the lock and securing the same in unlocked position. Then, upon release of the lever 40, that is, when the door has opened, the shaft 44 will rotate sufficiently for the lever 40 to return to horizontal position, as in Fig. 3, independently of the unlocked condition of the locking mechanism; the tooth 80, during this return 85 movement of the lever 40, moving in a clockwise direction from the position indicated in Fig. 26 so as to occupy the position indicated in Fig. 27. Thus, the wedge bolt is permitted to assume lowered position as shown in Fig. 3 and the parts shown in Fig. 27 will remain in such position until the door is locked when they will return to the position shown in Fig. 25. The advantage of this particular feature will appear 90 later.

The rod 48, which was above referred to as being operated by rotation of the shaft 44, extends out through the right-hand end of the tripper case and is connected by means of a flexible chain 90 to one arm of a bell crank lever which is pivoted at 91 to the bracket 92 depending from the top of the track box. The other arm of this bell crank lever is pivotally connected to the wedge strip 93, the other end of which has a cam portion 94 for engagement with the roller 95, which in turn is pivotally mounted in the lower end of the bracket 96 suspended from the top of the track box. Mounted for movement along the top edge of the wedge strip 93 there is provided the roller 97 which carries the wedge bolt 98. This bolt extends downwardly through registering openings in the overlying flanges 99 of the bracket which is suitably secured to the strip on the door hanger member and occupies position directly in front of the door roller 8. Thus, it will be seen that upon movement of the rod 48 to the left, as viewed in Figs. 1, 2 and 3 of the drawings, the wedge strip 93 will be raised so as to raise the bolt 98 and effect release of the same from locking engagement, as will later appear. The lower end of the wedge 100

bolt 98 is adapted for engagement in the recess 100 provided in the upper side of the gap nut 101 which is adjustably mounted upon the pull bar 102. The gap nut has the low shoulder portion 103 and the high shoulder portion 104.

The adjustment of the gap nut 101 is effected by loosening the nut 105 which engages the threaded portion 106 of the pull bar and engages also the one end of the gap nut as well as the one end of the threaded sleeve 107. The other end of sleeve 107 is formed as a nut 108 engaging the other end of the gap nut, the threads on the adjacent end portions of the bars 102 being of the same hand, as for instance right hand. Thus, upon loosening the nut 105, the sleeve 107 can be moved in either direction along the pull bar and can be secured in such set position by means of the nut 105. The proper length of the pull bar can be obtained upon assembling the parts by turning one of the bars in the gap nut and holding the adjacent bar still. The gap nut is provided with rollers 109 on the two sides thereof for rolling engagement within the channel guideway 110 provided in the bottom of the track box. It is upon the one side wall of the channel guideway 110 that the angle plate 13 is mounted. The pull bar, upon which are provided as many gap nuts as there are doors and in the same manner as just now described, has its left-hand end secured to the slidable rack 111 which is provided also with rollers 112 for movement along the bottom of the channel guideway 110. The rack 111 is engaged by the gear 113 which engages also the rack 114 fixed in the top of the track box. The gear 113 has a link connection 115 to the crank arm 116, which, in turn, is fixed upon the pinion 117. This pinion meshes with and is operated by the rack 118 which is suitably mounted within the lock box and which has its lower end operated by means of the pinion 119 secured upon the shaft 120 of the lever arm 121. The shaft of lever arm 121 extends out through the side of the compartment 3^b and the lever arm 121 is entirely outside of compartment 3^b but within the lock box. The lever arm or handle 121 is held in lowered position by means of the spring fingers 122 and may be held in raised position by the same means indicated at 123. The lowered position of the handle 121, as in Fig. 1, corresponds to locked position of the doors; in which position the wedge bolt 98 occupies the position shown in Fig. 1 and by its engagement with the higher shoulder portion 104, the door is further held closed. While the handle 121 occupies such position, however, the wedge bolt 98 occupies position slightly above the lower shoulder 103 of the gap nut so as to permit operation of the handle 121 to move

the pull bar to the right along the track box for the purpose of picking up and closing any door which might have been left open. In other words, the wedge bolt 98 of door No. 1, when in locked position, does not interfere with movement of the gap nut to the right as is necessary in order to close door No. 2 by means of the pull bar. The raised position of the wedge bolt 98, as just referred to, is effected by means of the wedge lift crank 124 which is pivotally mounted upon the bracket 96 and which is engaged by the adjustable projection 125 provided upon the bracket through which the wedge bolt extends. Thus, when the door is brought to closed position, the lift crank will be raised by the projection 125 so as to cause the upper arm 124^a of the lift crank to engage the end portion of the wedge bar and raise the same with the wedge bolt 98.

With all of the doors locked, the lever arms 40 will occupy the position indicated in Fig. 1 so as to indicate such condition of the doors. At this time, the plunger carried by the door will be in engagement with the block 71 so as to maintain the shaft 58 in such position as to hold the shield withdrawn. When, however, it is desired to open any one or more of the doors, the corresponding lever or levers 40 are fully depressed to a position indicated in Fig. 2, as a result of which the shaft 44 in each case is rotated in a counter-clockwise direction and the pawl 26 will snap into engagement with the shoulder 30 so as to maintain the lock bolt 21 in withdrawn position. At the same time, the rod 48 by virtue of its movement to the left in the manner above described will cause actuation of the wedge strip 93 so as to raise the wedge bolt 98 in each case and permit passage of the same towards the right and over the gap nut. The spring 74 which has been held under tension is now released and automatically forces the door to open position to the extent indicated in Figs. 2 and 3 of the drawings. The door can then be fully opened by the occupant or the warden. Likewise, the door of any one of the cells can be individually closed by the prisoner or the warden by simply moving the same to fully closed position without having to resort to the lock box. It will be understood that upon fully closing the door, the rod or pin 71^a will disengage the pawl 55 from the shoulder 54 and will thereby release the lock bolt for locking engagement, the movement of the roller 70 as caused by the plunger 78 having at the same time caused rotation of the shaft 58 so as to withdraw the shield 36 from closed position. As soon as these parts are released in the manner just described, the handle or handles 40 will be permitted to return to fully raised position, as in Fig. 1, 130

so as to indicate that the corresponding door or doors have been fully closed and effectively locked.

In the opening operation of any of the doors, the wedge bolt 98 will be raised to the position indicated in Fig. 2, that is, when the lever 40 is fully depressed; and upon releasing the lever 40, which is made possible without affecting the locking mechanism in the lock case by virtue of the lost motion connection, the wedge bolt will drop to occupy the position indicated in Fig. 3 of the drawings, and the lever 40 will maintain such horizontal position so long as the door remains open and unlocked. The wedge bolt 98 is free to occupy this extreme lowered position at this time, since it is free of the influence of the wedge lift crank 124. With the wedge bolt in this lowered position, it will be seen that the same can be engaged by the gap nut of the corresponding door so as to occupy fully lowered position in the recess 100 of the same and to effect movement of the door to fully open or closed position, as may be desired. This is effected by raising the lever handle 121 so as to move the gap nut toward the right, whereupon the wedge bolt will ride up the inclined face of the high shoulder portion 104 and drop into the recess 100. In case the door is moved to fully open position by this means, the adjustable plunger pin 126 on bracket arm 79 will engage the spring button 127 mounted upon the bracket 128 secured to the top of the track box. Such engagement will place the spring 129 under compression so that, should the wedge bolt be raised by depressing the proper lever 40 while the door occupies such fully open position, the tension of the spring 129 will force the door toward the left a sufficient distance to free its wedge bolt of the gap nut and thereby render the same free for closing independently of the other doors which may be maintained in fully open position.

Should, however, it be desired to close at one time all of the doors which are in open position, this is accomplished by raising the handle 121 so as to move the gap nuts toward the right so as to pick up the wedge bolts of the doors which are in open position. It will be understood, of course, that the wedge bolts of any doors which are already locked, will ride up the high faces of the gap nuts but will not be engaged by the lower shoulder portions of the gap nuts since the wedge bolts of the closed doors are by means of the wedge lift crank maintained at an elevation above the level of the lower shoulder portions of the gap nuts. When the wedge bolts of the open doors are engaged by the gap nuts, the handle 121 will be lowered to the position indicated in Fig. 1, thereby causing the door

staple in each case to actuate the plunger within the lock casing and release the lock bolt so as to effectively interlock with the door staple, the shield being at the same time withdrawn in the manner above described. Also at the same time, the plunger carried by the door hanger will enter the tripper case and cause the plunger rod 46 to engage pawl 55 so as to release the shaft 44 and permit the lever 40 to return to fully raised position and thereby indicate that the door has been fully closed and effectively locked.

The pilasters are provided with removable covers 130 which are provided with headed pins 131 for engagement in the key-hole slots 132 formed in the inwardly extending flanges 133. These covers are in each case supplied by inserting the heads 131 through the enlarged portions of the slots 132 and then raising the covers, whereupon the screw bolt 134 is extended through the bottom of the track box so as to engage the inwardly extending lug 135 formed on the inner face of the pilaster cover. In this way, the covers 130 are maintained in the raised position indicated in Fig. 8. The cover plates 136 for the track box are provided with locking fingers 137 to engage over the upwardly extending flange portions 138 at the front of the bottom of the track box. The dowel pins 139 which are provided upon the inner face of the covers 136 are so spaced as to engage the lower ends of the lugs 140 which are fixed upon the rod 141 when the rod 141 occupies locked position and thus prevent the covers from being raised. The pins 136 on flanges 136^b of the covers engage in openings in the top of the track box and prevent the tops of the covers from being pulled outwardly or forwardly by an unauthorized person. The lugs 140 have also lug portions 140^a which engage the inner face of the flange 142. The rod 141 is adapted to be moved transversely in the track box which is provided on its depending flange 142 with suitable brackets 143 for supporting the same. This rod is connected at its one end to the rock arm 143 which is suitably pivoted at the point 144 and has its other end pivoted to the connecting link 145 which in turn is pivoted to one arm of the bell crank lever 146. The lever 146 is pivoted at the point 147 to a suitable bracket mounted within the lock box and has pivotal connection with the rod 148 which in turn has its other end connected to the operating lever arm 149 which is also pivoted at the point 150 within the lock box. The lever arm 149 extends through a slot in partition 3^b and is limited in its movement by the ends of the slot so as to determine proper locked and unlocked positions for the same. The arm 149 is also provided with a depending finger 151 for engagement by the bolt 161 which locks the

lever in cover-locking position. The lever arm can also be locked by the bolt in lowered position as indicated in Fig. 5. A cover 136 is provided for each section of the track box corresponding to each door, and these covers are arranged to abut each other, all of these covers being, however, locked by lugs 140 on the same rod 141 which extends the full length of the entire battery of cells. 10 Thus, it will be seen that in order to gain access to the lock case 19 and also to the mechanism contained within the track box, it is necessary first to depress the handle 149 so as to disengage the lugs 140 from the 15 dowel pins 139. The cover of the particular track box, to which access is desired, can then be removed, and if desired, the pilaster cover 130 can also be removed by removing the screw bolt 134. In case it should be 20 desired to have access to the mechanism in connection with only one of the doors, the lever 149 is returned to locking position as soon as the track box cover for that particular door is removed, and in this way unauthorized access to the control mechanism of 25 any other of the doors is prevented. In cases where a large number of cells are used I have provided an improved means for 30 guiding the chain connections between the operating levers in the lock box and the lock mechanism for the several doors. In Fig. 38, for instance, I have illustrated an arrangement in which there are twelve cells with an 35 improved means of leading or directing the chain connections so as to utilize to the best possible advantage the limited amount of overhead space between the top of the lock box and the ceiling. In this particular arrangement it will be noted that the chain 40 connection for door No. 1 is led over a roller which is mounted on a stub shaft 152 in the roller bracket 153; the chain for door No. 2 is led over a like roller mounted in bracket 154; the chain for door No. 3 is led over a 45 roller mounted in bracket 155; and likewise the chains for doors Nos. 4, 5, 6 and 7 are led over rollers mounted in brackets 156, 157, 158 and 159, respectively. These roller brackets have arms which constitute 50 means of mounting the same upon the bottom side of what I have termed the chain guide box, as clearly illustrated in Fig. 44. According to this figure, it will be seen that 55 brackets 153, 154 and 155 are secured to the bottom of the chain guide box by means of the same bolt and that the other remaining brackets are mounted by means of another bolt. As will be observed from the several 60 figures illustrating this particular form of device, the several roller brackets here shown are arranged at varying angles, which arrangement makes it possible for the chains from the several levers which are arranged horizontally across the lock box, to be lead 65 out through the same restricted opening in

the back wall of the lock box. These chains are then lead through the track box in vertical arrangement to the lock mechanisms for the particular doors. As shown in Fig. 37, the levers are arranged in two rows and in 70 staggered relation so as to provide ample space for the hand of the operator in grasping the same. It will be understood that the chains have the same operative connections at their far ends as in the first form of device here illustrated, and the mechanism is otherwise the same except as herein pointed out. 75

The chain guide box, above referred to, is suitably supported in the overhead space at 80 the top of the lock box and comprises a stack or nest of partition plates 160 which are separated by means of spacers 161, these parts being secured together by means of tie bolts 162 which clamp the top and bottom 85 plates. Extending also through the chain guide box I have provided bolts 165, 166 and 167 upon which are rotatably mounted the sets of rollers 168, 169 and 170, these rollers being of slightly less thickness 90 than the spacers 161 so as to be free for rotation. The rollers just referred to serve as a guide means for the chains as they pass about the same as clearly illustrated in the drawings. It will be observed that the 95 chains are of the sprocket link type but the links throughout one section of the chain are connected so as to provide bending of the chain in one direction, whereas another section of the chain has its links so connected as to be bent at 90 degrees to the other section. This arrangement is for the purpose of having the chain guided in the different directions as clearly illustrated in the 100 drawings. 105

It will be observed from the drawings that the chain corresponding to door No. 1 as it extends out into the track box is the lowermost of the vertical series of chain connections. The chain corresponding to door No. 2 after passing about the roller in bracket 110 154 extends also about one of the rollers 168 which are mounted on the same bolt 165. The chain corresponding to door No. 3 extends through on a straight line. The 115 chain corresponding to door No. 4 after passing about the roller in bracket 156 passes about one of the rollers 169. The chain corresponding to door No. 5 after passing about the roller mounted in bracket 157 extends 120 about one of the rollers 169, and likewise the chains corresponding to doors Nos. 6 and 7 after passing about rollers mounted in brackets 158 and 159 extend about other rollers 169. With this arrangement it will 125 be seen that all of the chains after passing about their several rollers as just described will extend out through the track box in over-lying arrangement with the chain corresponding to door No. 1 occupying lower- 130

most position, chain No. 2 occupying the position directly above chain No. 1, and the chain corresponding to the last door occupying uppermost position.

As a means of taking care of the chain connections from the levers of the other five doors in this particular case I have provided other rollers 171 and 172 which are shown in detail in Fig. 40 and which are arranged alternately in the front and rear spaces 171^a and 172^a, these rollers being mounted in substantially the same manner as those in the chain guide box above described. These spaces are formed between plates 173, 174 and 175 which are secured together by means of tie bolts 176 and spacers 177. The rollers 171 and 172 occupy what might be termed a diagonal arrangement as shown in Fig. 40, by virtue of which the several chains as they are led over these rollers are passed out into the track box in vertical arrangement, as clearly illustrated in Fig. 38. This series of guide rollers 171 and 172 is arranged to one side of the chain guide box and is spaced from the rear wall of the casing so as to occupy proper relation with respect to the rollers 168, 169 and 170. The chain corresponding to door No. 8 is passed through compartment 172^a and about the lowermost roller 172 and thence about roller 169 from which point it passes out into the track box immediately above chain No. 7. Chain corresponding to door No. 9 extends about one of the rollers 171 in the front compartment 171^a; the chain corresponding to door No. 10 extends about the next one of the rollers 172 which is located in the rear compartment 172^a, and so on throughout the entire number of chains. It will be observed that chains corresponding to doors Nos. 8, 10 and 12, that is the even numbered chains, extend about rollers 172 and then about the rollers 169, rollers 172 being provided in alternate compartments of the chain guide box as indicated in Figs. 42 and 43. The rods or wire to which the several chains are connected in the track box extend through guideways provided in the bracket 179 secured upon the rear wall of the track box as clearly illustrated in Fig. 45.

In the case in which thirty-four doors are controlled from the same lock box, the arrangement is somewhat the same as in the preceding case of twelve doors. In the case of thirty-four doors however, the chains and rods which are led out through the track box are arranged in horizontal pairs as illustrated in Fig. 55; and a chain guide box is employed like that used in the case of twelve doors except that it is higher so as to accommodate a greater number of chains. In the present case six of the chains are led over rollers mounted in three pairs in brackets which in turn are supported from

the bottom side of the chain guide box as illustrated in Fig. 47. The main bracket 180, which comprises the roller brackets 180^a and 180^b for chains Nos. 1 and 2, is mounted at the point 180^c while the other two main brackets 181 and 182 which comprise roller brackets 181^a, 181^b, 182^a and 182^b for chains Nos. 3, 4, 5 and 6 respectively, are mounted together at the point 181^c. The partition plates 183 are separated by means of spacers 184 in the same manner as in the previous case and are all secured together in the same manner by means of tie bolts. In this case there are provided the three sets of rollers 185, 186, and 187 which are mounted in the partitions provided between the plates 183 in the same manner as in the previous case except that the arrangement of these rollers is somewhat different according to the manner of leading the chains thereto. As will be seen from the Figs. 47 and 48 and other detail views, chain No. 1 after passing about its roller in bracket 180 passes also about roller 186 and extends out through the back wall of the lock box into the tracker box where it is connected to the rod or wire for operation of the door lock mechanism, the mechanism being otherwise the same as above described. Chain No. 2 extends straight through the partition in the chain guide box and out into the track box. Chain No. 3 after passing over the roller in its bracket 181 extends about roller 185 and then about roller 186^a and passes out into the track box immediately above connection No. 1. It will be observed in following through the several chain connections that the odd numbered chains extend about the rollers 185 while the even numbered chains extend about the rollers 187^a as clearly illustrated in the drawings. Chain No. 7 and the chains thereafter up to and including chain No. 34 extend about the several rollers 186^a and 187^a which are arranged alternately in the front and rear compartments 186 and 187, respectively, these compartments being formed by means of plates 188, 189 and 190. The two succeeding rollers in each case have the same elevation, as seen in Fig. 46, so as to pass out through the track box in vertically arranged pairs, as shown in Fig. 38. The odd numbered chains pass about the rollers in the front compartment while the even numbered chains pass about the rollers in the rear compartment, this arrangement being substantially like that in the previous case of twelve doors. It will be observed that in this case, as in the preceding case of twelve doors, the chains of the highest number as for instance, chains Nos. 33 and 34 occupy the uppermost position as viewed in Fig. 55.

Another improved feature of my device consists in the particular gear combination

for operating the pull bar which carries the gap nuts for moving the doors to fully opened or closed position. This reduced gear combination by which the operation of these parts is greatly facilitated is illustrated in Fig. 49, in which reference numeral 191 indicates a shaft which is adapted to receive a removable crank handle for turning the same. Shaft 191 carries the 10 pinion 192 which meshes with the gear 193 fixed on shaft 194, the last named shaft having fixed thereon pinion 195. The last named pinion meshes with rack 118, this being the same rack which is shown in Fig. 15 1 for operation of the gear 117 which in turn has a crank connection with the main gear 113 for reciprocating the rack bar connected with the gap nut pull bar. The advantage of this particular gear combination 20 shown in Fig. 49 consists in the ease with which the great number of doors can be moved along their track ways, the gear ratio shown being particularly adapted for this purpose. This particular arrangement 25 serves as a substitute for the operating lever 121 shown in the first form of device and in the present form in which thirty-four doors are used as shown in Fig. 49, the shaft 191 will extend horizontally, which means 30 that the crank handle for operating the same will be rotated through a vertical plane. The free end of the shaft 191 extends through the cover 3^b of the casing which encloses the operating parts as shown 35 in Fig. 1, and upon opening the main door of the lock box the detachable crank handle may be attached to the protecting end of shaft 191 for operation of the same. I have provided also a stop 196 upon the rack 118 40 for engagement with the stop pins 197 which are suitably mounted in brackets so as to be readily adjusted according to the limits of movement which are desired for the rack bar 118 according to the limits of movement 45 desired for the gap nuts.

What I claim is:—

1. A jail door locking mechanism comprising a lock bolt adapted for movement into and out of locking position, means for holding said lock bolt in unlocked position, and means carried by the door for releasing said holding means and adapted to be engaged by said lock bolt for locking the door. 50

2. A jail door locking mechanism comprising a lock bolt adapted for movement into and out of locking position, spring actuated means for engaging and holding said lock bolt in unlocked position upon unlocking the same, and means adapted for actuation by closing of the door for releasing said holding means and permitting locking engagement between said lock bolt and said releasing means. 60

3. A jail door locking mechanism comprising a spring actuated lock bolt tending

to normally occupy locked position, means for holding said lock bolt in unlocked position, and means carried by the door for releasing said lock bolt so as to engage said means carried by the door and lock the same. 70

4. A jail door locking mechanism comprising a lock bolt adapted for movement into and out of locking position, means adapted to engage said lock bolt for holding the same in unlocked position, and means carried by the door for releasing said holding means and permitting locking of the door. 75

5. A jail door locking mechanism comprising a casing, a lock bolt in said casing and adapted for movement into and out of locking position, means in said casing for holding said lock bolt in unlocked position, and means adapted for actuation by closing of the door for releasing said holding means 80 and permitting locking of the door. 85

6. A jail door locking mechanism, comprising a casing, a lock bolt in said casing and adapted for movement into and out of locking position, means in said casing for holding said lock bolt in unlocked position, and a keeper carried by the door and adapted to release said holding means upon closing the door so as to permit locking engagement between the lock bolt and keeper. 90 95

7. In a jail door mechanism, the combination of a door, separate means for locking said door closed, a single operating means for controlling said locking means, one of said locking means being adapted to unlock ahead of the other, and operative connections in said controlling means whereby further actuation of one of said locking means may be effected for releasing the same without affecting said other locking means. 100 105

8. In a jail door mechanism, the combination of a door, separate means for locking said door closed, and operative connections between said locking means whereby one of them can be further actuated without 110 affecting the other, said operative connections including a lost motion connection.

9. In a jail door mechanism, the combination of a door, means for locking said door, means for operating said locking means and indicating open or closed condition of the door, said means being so constructed and arranged that the open position of the door will be so indicated until the door is actually closed and locked. 115 120

10. In a jail door mechanism, the combination of a door, means for locking said door, means for operating said locking means and indicating open or closed condition of the door, said means including means 125 for holding said operating means in open position and for preventing release of said holding means until the door is closed and locked.

11. In a jail door mechanism, the com- 130

- bination of a door, means for locking said door, means for operating said locking means and indicating open or closed condition of the door, said means including means for holding said operating means in open position and means for releasing said holding means upon said door being fully closed.
12. In a jail door mechanism, the combination of a door, means for locking said door, means for operating said locking means and indicating open or closed condition of the door, said means including means for holding said operating means in open position and means on the door for releasing said holding means upon said door being fully closed.
13. In a jail door locking mechanism, the combination of a door, means for locking the door, a removable cover for said locking mechanism preventing unauthorized access thereto, means for locking said cover, and means for controlling the locking means of the door and cover from the same point.
14. In a jail door locking mechanism, the combination of a plurality of doors, control means for each door, an individual removable cover for the control means of each door preventing unauthorized access thereto, means for releasably locking said covers whereby any given cover can be released and removed and the other cover or covers maintained locked.
15. In a jail door locking mechanism, the combination of a door, a lock for the door, control means for the lock, separate covers for the lock and control means, means for locking one of said covers, and means whereby the locking of said one cover prevents removal of said other cover.
16. In a jail door locking mechanism, the combination of a door, means for locking the door at the top and side, separate covers for the top and side locking means, means for removably securing one of said covers, and means for locking the other cover so as to prevent removal of said first cover.
17. In a jail door locking mechanism, the combination of a door, and means comprising a reciprocatory member for producing opening and closing movement of the door, said member being adjustable whereby the proper relation of the same may be obtained with respect to the door.
18. In a jail door locking mechanism, the combination of a door, a releasable engaging member carried by the door, and a reciprocating member adapted for engagement with said releasable member, said reciprocating member being adjustable in the direction of its path of travel so as to obtain proper engaging relation with said other member.
19. In a jail door locking mechanism, the combination of a sliding door, a releasable depending engaging bolt carried by the door, a gap nut having a recess to receive said bolt, a reciprocating pull bar, a sleeve having adjustable engagement with said bar, and said gap nut being removably secured upon said sleeve, whereby said gap nut can be adjusted to proper position with respect to said bolt.
20. In a jail door mechanism, the combination of a door, a track upon which said door is slidably mounted, a casing enclosing said track, and means for preventing tampering with the slidable mounting of the door.
21. In a jail door mechanism, the combination of a slidable door, a track box, a track in said box, a roller having engagement with said track, said door having a connecting means through an opening in the box to said roller, and means for preventing access to said track and roller through said opening in the box.
22. In a jail door mechanism, the combination of a slidable door, a track box, a track in said box, a roller having engagement with said track, said box having an opening, a plate in said box preventing access through said opening to said track and roller, and a connection between said door and roller through said opening.
23. In a jail door mechanism, the combination of a slidable door, a track box, a track in said box, a roller having engagement with said track, said box having an opening, baffle means in said box preventing access through said opening to said track and roller, and a connection between said door and roller through said opening.
24. In a jail door mechanism, the combination of a door, a track upon which said door is slidably suspended, and means for adjusting the angular relation of the door to the track so as to correct the position of the door in its opening without disturbing its slidable connection.
25. In a jail door mechanism, the combination of a door, a suspension means to which said door is adjustably connected, a track, and a roller means carried by said suspension means for slidable engagement with said track, said adjustable connection permitting correction of the relation of the door to the door opening.
26. In a jail door mechanism, the combination of a plurality of doors, means for locking said doors, means including operating levers and individual flexible connecting means for operating said locking means, said levers being arranged horizontally, and means for directing said several connecting means in vertical arrangement to the several doors.
27. In a jail door mechanism, the combination of a plurality of doors, means for locking said doors, a track box above said doors, a lock box, a plurality of operating

levers arranged horizontally in said lock box, individual flexible connections between said levers and said door locking means for operating the same, and means for directing 5 said several connecting means from said lock box so as to extend in vertical arrangement in said track box.

28. In a jail door mechanism, the combination of a plurality of doors, means for 10 locking said doors, means including operating levers and individual flexible connecting means for operating said locking means, said levers being arranged horizontally, means for directing said several connecting 15 means in vertical arrangement to the several doors, said directing means including a plurality of rollers mounted upon axes arranged at an angle to each other, and said connections including chains adapted for 20 bending in only two directions at substantially ninety degrees to each other so as to be directed about said rollers.

29. In a jail door mechanism, the combination of a plurality of doors, means for 25 locking said doors and means including operating levers and individual flexible connecting means for operating said locking means, said levers being arranged in a plurality of horizontal sets with the levers of 30 one set staggered with relation to the levers of another set, and means for directing said several connecting means in vertical arrangement to the several doors.

30. In a jail door mechanism, the combination of a plurality of sliding doors, re- 35

leasable depending engaging bolts carried by the doors, gap nuts having recesses to receive said bolts, a reciprocating pull bar, and means including a reduction gear combination for operation of said pull bar. 40

31. In a jail door mechanism, the combination of a plurality of sliding doors, re- 45 leasesable depending engaging bolts carried by the doors, gap nuts having recesses to receive said bolts, a reciprocating pull bar, means for operating said pull bar, and means for limiting the travel of said gap nuts.

32. In a jail door mechanism, the combination of a plurality of sliding doors, re- 50 leasesable depending engaging bolts carried by the doors, gap nuts having recesses to receive said bolts, a reciprocating pull bar, means for operating said pull bar, and stop means for said operating means to determine the range of movement of said gap nuts. 55

33. In a jail door locking mechanism, the combination of a sliding door, a releasable dependable engaging bolt carried by the door, a gap nut having a recess to receive said bolt, a reciprocating sectional pull bar 60 having adjacent end portions threaded with the same hand thread, a sleeve threaded upon said adjacent threaded end portions for adjustment thereon, and said gap nut being removably secured upon said sleeve, 65 whereby said gap nut can be adjusted to proper position with respect to said bolt.

In testimony whereof I hereby affix my signature.

JOHN T. WHITEHOUSE.
